UNITED STATES PATENT OFFICE.

BENTON P. O'HARE, OF NASONVILLE, RHODE ISLAND.

COLLAPSIBLE BOX.

Application filed September 17, 1923. Serial No. 663,157.

To all whom it may concern:

Be it known that I, BENTON P. O'HARE, a citizen of the United States, residing at Nasonville, county of Providence, State of 5 Rhode Island, have invented certain new and useful Improvements in Collapsible Boxes, of which the following is a specification.

This invention relates generally to boxes, 10 and particularly to collapsible boxes; the primary object of the invention being to provide a structure adaptable particularly for use in the shipment of woolen or worsted piece goods, which will prove durable strong 15 and rigid when set up or extended, and which may be readily collapsed or folded when relieved of its contents, so as to occupy but a small amount of space.

A further object is to so construct the 20 box that the principal hinges thereof will be housed by the box structure so as to be protected thereby, and, furthermore, so as to offer no obstruction to proper piling or handling of the boxes.

25 A still further object is to provide a box of the character and for the purposes set forth, featured by novel means for connecting the hinge members with the side, end, bottom and top panels of the box, whereby 30 to greatly reinforce both the panels and the hinge members.

35 Still further objects are to provide a collapsible box which may be constructed easily and at small expense, which is made or constructed in such manner as to present the greatest possible strength both in set up and collapsed positions, which tightly holds its contents when in use as a shipping container, which is composed of comparatively 40 few simple and readily assembled parts, which has its parts so constructed and arranged as to minimize the opportunity for wear, breakage or derangement, and which will prove thoroughly practical and efficient 45 in use.

With these objects in view, together with others which will appear as the description proceeds, the invention consists in the novel construction, combination and arrangement 50 of parts, all as will be described more fully hereinafter, illustrated in the drawings, and particularly pointed out in the claims.

In the drawings:

55 Fig. 1 is a perspective view of a box con-

structed in accordance with the invention, as it will appear in set up position.

Fig. 2 is an edge view of the box as it will appear collapsed,

Fig. 3 is a transverse central sectional view 60 taken through the box in set up position, and

Fig. 4 is an enlarged detail sectional view 65 showing the formation and arrangement of one of the hinges.

The box in the present instance is adapted particularly for use in the shipment of woolen or worsted piece goods and for properly protecting and housing the same in transportation, however, it will be understood that the box or its inventive features may be as effectively employed with boxes or shipping or storing cases to be used in other capacities. The box of my invention is preferably made of sheet metal so as to 70 properly protect its contents, to resist wear and strains, and to enable the same to be folded or collapsed into small compass.

In detail, the box comprises front and 75 rear side panels 5 and 6; end panels 7 and 8; a bottom panel 9, and a top or closure panel 10, all hinged together. These panels will be made of such size as to adapt the box for the required uses, and they may or may not, as desired, be corrugated.

80 The side, or front and rear, panels 5 and 6 are hinged at their ends with the end panels 7 and 8, and the hinges are preferably coextensive with these members. 90 These hinges, furthermore, are so arranged that they will be housed by the box when the latter is set up, so that protection is afforded them. The bottom panel 9 is hinged as at 11 to the lower edge of the front panel, 95 while the top 10 is hinged as at 12 to the upper edge of the rear panel 6; the hinges of both these members being coextensive with the longitudinal edges of the front and rear panels.

100 The bottom panel 9 is provided upon its free edges with up-standing aprons or flanges 13, to enclose the lower edges of the end and rear panels and to tightly grip the same, thus securely closing the joints of 105 these members, and any preferred means may be employed for holding the bottom panel in closed position. In the present instance, the bottom panel is equipped with hooks 14 to engage in eyes 15 on the inner 110

faces of the end panels to securely hold these parts in assembled or set up position. The top may be fastened in closed position in any approved or desired manner.

5 The several hinges connecting the various panels are of identical construction, and may be described as comprising generally a series of spaced barrel portions 16, at the outer edges of spaced arms 17; the latter 10 engaging and embracing the edge of the panel to which the particular hinge member is applied. The hinge members are co-extensive with their respective panels, so as to reinforce the latter from end to end, and, in 15 turn, to be stiffened or reinforced by the panel to which it is applied.

The hinges may be constructed of comparatively thin metal strips, bent upon themselves longitudinally and medially to 20 form the hinge sleeves or barrels, as shown, and to provide the rearwardly extending spaced arms 17. In practice, the hinge members are applied by inserting the edges of the panels between the spaced arms 17 25 and securing the arms to the panels by soldering, riveting or spot welding. The barrels or sleeves on adjoining hinge members are spaced apart so as to interfit with each other, and hinge pins are inserted in the 30 aligned sleeves to hold the same together.

The sleeves or barrels of the panels 5, 6, 7 and 8 are offset from the main body portions of the hinge members, as shown particularly in Figs. 2 and 4, so that the same 35 will be wholly housed by the box ends and sides when the latter is in set up position. This arrangement affords protection to the hinges and obviates protruding parts to interfere with handling or storing of the 40 boxes in transportation. It also enables the boxes to be properly collapsed when empty.

From this construction is apparent that I 45 have provided a collapsible box of extreme simplicity, and yet one which will prove fully capable of attaining the several objects set forth. The construction of the panels and the manner in which the hinge

members are assembled upon the same enables the box to be made or assembled by simple processes and at comparatively small expense, while at the same time providing 50 reinforcing means of such character as to prevent collapsing, crushing or breaking of the box in the rough treatment they usually receive in transportation. 55

The above is a description of the invention in its preferred embodiments, however, it will be understood that variations in the several details of construction, the arrangement and assemblage of parts may be resorted to if desired or required without departing from the spirit of the invention as defined by the claims.

Having thus described my invention, I 65 claim:

1. A box comprising side and end panels, co-operating hinge members for the edges of each panel, said members comprising metal strips bent upon themselves to form hinge barrels and each embracing both faces of the panel with which it is associated, and hinge pins connecting said barrels. 70

2. A box comprising side and end panels, interfitting hinge members on the adjacent ends of each of said panels, each hinge member comprising spaced arm portions embracing the edge of the panel with which it is associated and spaced barrels adapted to interfit with the barrels of the hinge member of the next adjacent panel, and pins connecting said barrels. 75

3. A box comprising side and end panels, interfitting hinge members on the adjacent ends of each of said panels each member being coextensive with its respective panel and comprising spaced arm portion embracing the edge of the panel with which it is associated and spaced barrels adapted to interfit with the barrels of the hinge member of the next adjacent panel, and pins connecting 80 said barrels. 85

In testimony whereof I affix my signature.

BENTON P. O'HARE.
